(57) **CLAIM**

The ornamental design for a microfluidic cartridge, as shown and described.

DESCRIPTION

FIG. 1 is a bottom front right perspective view of a microfluidic cartridge showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof; and,

FIG. 7 is a right side elevation view thereof.

The broken lines are included for the purpose of illustrating portions of the microfluidic cartridge that form no part of the claimed design.
